GOLF CLUB HEAD

George C. Brower, 2308 Pacific Ave.,
Long Beach, Calif. 90806

Filed Apr. 3, 1972, Ser. No. 240,883

Term of patent 14 years

Int. Cl. D21—02

U.S. Cl. D34—5 GH

FIG. 1 is a perspective view of the golf club head showing my new design;

FIG. 2 is an elevational view showing the front face of the golf club head;

FIG. 3 is a top plan view of the golf club head;

FIG. 4 is an elevational view showing the rear face of the golf club head;

FIG. 5 is a bottom plan view of the golf club head;

FIG. 6 is an end elevational view of the golf club head; and

FIG. 7 is an end elevational view of the golf club head of the end thereof opposite to that shown in FIG. 6.

The hosel portions of FIGS. 2—6 are shown fragmentarily for convenience of illustration.

I claim:

The ornamental design for a golf club head, as shown and described.
